UNITED STATES PATENT OFFICE.

WILLIAM EDWARD FOWLER, JR., OF HAMMOND, INDIANA.

RUNNING-BOARD FOR FREIGHT-CARS.

1,019,627.

Specification of Letters Patent.

Patented Mar. 5, 1912.

Application filed October 12, 1911. Serial No. 654,424.

To all whom it may concern:

Be it known that I, WILLIAM E. FOWLER, Jr., of Hammond, in the county of Lake and State of Indiana, have invented certain new and useful Improvements in Running-Boards for Freight-Cars, of which the following is a specification.

This invention relates to improvements in running boards such as are ordinarily placed upon the tops of freight cars for the purpose of permitting the train men to walk along the tops of the cars, and the objects I have in view are to provide a running board of this character, which will be simple in construction, and which will automatically free itself from ice or snow accumulating thereon, and which will present a surface upon which a person may walk without danger of slipping therefrom.

The invention consists generally in the constructions and combinations hereinafter described and particularly pointed out in the claims.

In the accompanying drawing, forming part of this specification, Figure 1 is a plan view, partly broken away, of a running board embodying my invention, Fig. 2 is a side elevation of the same, Fig. 3 is an elevation of the supporting saddle with the side rails secured thereto and the expanded metal top secured to the side rails, Fig. 4 is a similar view showing modified means for securing the expanded metal to the side rails, Fig. 5 is a similar view showing especially formed side rails to which the edges of the expanded metal sheet are secured. Fig. 6 is an elevation of one of the end braces, Fig. 7 is an elevation of one of the intermediate braces.

In the drawings, 2 represents one of the saddles, which consists of a metal bar having a depressed center 3, ends 4, adapted to be bolted or secured to the car top, and standards 5 extending upwardly from said ends 4. The depressed center 3 forms a pair of standards 6—6, and the center of said depressed portion is preferably provided with a bolt hole 7, by means of which said supporting saddle may be centrally secured to the car top. Flanged rails 8—8 are preferably riveted to the standard 5. These rails extend the full length of the car body and preferably project slightly beyond the ends of the car as indicated at the left in Fig. 2 of the drawings. I also prefer to provide intermediate braces 10 as shown in Fig. 7 of

the drawings, said braces being riveted to the vertical flanges on the bars 8, as indicated in Fig. 1 of the drawings. At each end of the running board, I prefer to provide an end brace 11 which has standards 12 that are riveted to the vertical flanges of the side rails 8, preferably at the ends thereof, and project below said side rails and are riveted at their lower ends to diagonal braces 13 that are in turn secured upon the ends of the car body. The said saddles 2, the side rails 8, intermediate braces 10 and the end braces 11, form a rectangular frame that is rigidly secured to the car top. Upon this frame I secure a sheet of expanded metal, having preferably diamond shaped meshes as shown in Fig. 1 of the drawings. This expanded metal is arranged with the edges of the metal sheet forming the upper surface of the running board, as shown in Fig. 1 of the drawings. The edges of said sheet are secured to the side rails 8 in any suitable manner. I prefer to bend the edges of the sheet under the upper flanges of the side rails as shown in Figs. 1, 2 and 3 of the drawings. This makes a continuous locking support for the edges of said sheets and holds the sheets firmly upon the frame formed as hereinbefore described. If preferred, however, the edges of the sheets may be secured in place by washers 14 and rivets 15 which pass through the meshes of said metal sheet. If preferred I may provide specially formed side rails 15 having inwardly projecting flanges 17 and 18 with a space between them into which the edges of the metal sheet may extend and between which said edges may be clamped, as indicated in Fig. 5 of the drawings.

In each instance the metal frame is solidly secured to the car top and the sheet having the diamond shaped meshes, forming the surface that is to be walked upon, is secured rigidly at the edges to the side rails of said frame, leaving an open space between the top of the car and the under surface of said expanded metal sheet. The saddles and the intermediate and end braces firmly support said expanded metal sheets at suitable intervals so as to prevent the same from being pressed or bent downward out of shape. The edges of the metal sheet come uppermost and present rather sharp surfaces corresponding in width to the thickness of the metal, and these form a slightly elastic surface with diagonal bear-

ing lines upon which the weight of a person is received who walks or stands upon said running board. When snow or ice accumulate upon the top of this running board, the weight of a person standing or walking thereon will cause the snow or ice under the feet to be cut through by the edges of the metal and such snow or ice will then fall into the space between the expanded metal sheet and the top of the car. By this means the surface of the metal sheet will automatically free itself from snow and ice as a person walks over the same and, therefore, a person can walk on this running board with very little danger of slipping or falling therefrom.

I have shown in the drawings the expanded metal sheet arranged with the diamond shaped meshes extending crosswise 20 of the running board, and I prefer this arrangement. I can, however, if preferred, arrange the sheet with the meshes running lengthwise of the running board.

I do not limit myself to the details of 25 construction of the frame, or means of securing the edges of the metal sheet thereto, as the same may be varied in many particulars without departing from my invention.

I claim as my invention:

30 1. The combination, in a device of the class described, with longitudinally extending side rails, of transverse saddles, supporting braces connecting said rails, and an expanded metal sheet having its edges se-

cured to said side rails, substantially as described. 35

2. The combination, in a running board for freight cars, with longitudinally extending side rails, of a series of transverse saddles, supporting braces connecting said 40 rails and secured upon the top of the car, an expanded metal sheet having diamond shaped meshes therein, and means securing the edges of said sheet to said side rails whereby said sheet is held with a space between its under surface and the top of the car, substantially as described. 45

3. A running board for freight cars, comprising suitable saddles secured upon the top of the car, longitudinally extending side 50 rails secured to said saddles, and an expanded metal sheet having diamond shaped meshes, arranged with its edges secured to said rails, substantially as described.

4. The freight car running board, comprising the transverse saddles 2, having the end standards 5 and the central depression 3 with the standard 6, side rails 8 secured to said standard 5 and the expanded metal sheet resting upon the tops of said side rails 60 and saddles with its edges secured to said side rails, substantially as described. 55

In witness whereof, I have hereunto set my hand this 25 day of September 1911.

WILLIAM EDWARD FOWLER, JR.
